DEVICE AND METHOD OF MAKING
ORNAMENTAL DESIGNS

Samuel T. Daley, Akron, Ohio

Application February 13, 1940, Serial No. 318,728

1 Claim. (Cl. 164—125)

This invention relates to a device and method of making ornamental designs.

The general purpose of the invention is to provide a method and device for making ornamental designs in sheet material, such as cardboard, fibre board, or the like, for educational and amusement purposes.

One object of the invention is to provide a device of the character described, including a perforate card, preferably with uniformly spaced perforations in rows, whereby the material between perforations may be cut as desired to form designs in the card, there being an imperforate margin about the card to sustain the perforate portion, particularly at the edges thereof, during the design-cutting operations.

The foregoing and other purposes or objects will be manifest from the following brief description and the accompanying drawing.

Of the accompanying drawing:

Figure 1 is a plan view of a perforate card embodying the invention.

Figure 2 is an enlarged fragmentary view of a corner portion of the card shown in Figure 1, but with a design cut therein in accordance with the invention.

Figure 3 is a cross-section through a portion of a perforate card and illustrating the manner of cutting the material between the perforations.

Referring to the drawing, the numeral 10 designates a card having uniformly spaced rows of perforations 11, 11, the card being of suitable material adapted to be cut with a sharp tool. Extending about card 10 may be an imperforate margin 12.

In the practice of the invention, as for example as a game of amusement for children, a

number of cards 10 may be supplied in a container (not shown), together with a smooth sheet 13 of imperforate material, such as fibreboard, a short chisel-edged tool 14, and the usual directions or instructions for using the device. The sheet 13 is used as a backing for a card 10, while tool 14 is used to cut the material between adjacent perforations 11, as shown in full and chain-dotted lines in Figure 3. In this manner a great variety of designs may be formed inside the imperforate margin 12. This margin serves to sustain the perforate portion of the card, particularly at the edges thereof, while the design cutting operations are being performed.

The cards 10 may have designs cut therein for various practical uses, as well as for providing amusement. For example, the cards may have border designs cut therein to provide an ornamental backing for a picture, photograph, or the like.

Modifications of the invention may be resorted to without departing from the spirit thereof or the scope of the appended claim.

What is claimed is:

25 A device of the character described comprising a sheet of material having uniformly and closely spaced perforations, the material between the perforations being adapted to be cut with a sharp-edged tool to form a design in the sheet, 30 said sheet having an imperforate margin around the edges of said perforated portion, said margin being substantially wider than the material between adjacent perforations to sustain the perforate portion during or after the design-cutting operations.

SAMUEL T. DALEY.
